ABSTRACT OF THE DISCLOSURE

A laterally extending flange is cold-formed at an end of a thin metal cylindrical body by respectively providing a circular flanging die and a swaging roller with cooperating female and male peripheral radiused corners, and while an end of the body is axially aligned with the flanging die rotating the die and roller about parallel axes and moving them in opposite axial directions into engagement with the inner and outer sides of the body in a manner such that the flange is formed by the simultaneous application to the body of tensile and compressive forces.

BACKGROUND OF THE INVENTION**(1) Field of the invention**

This invention relates to a method of and apparatus for cold-forming a laterally extending flange at an end of a thin metal cylinder.

(2) Description of the prior art

When the ends of thin metal cylinders for can bodies are flanged by the conventional die flanging method the edges are subjected to basically tensile stresses due to the enlargement of the diameter. Die flanging is performed with a die having a widening contour which when forced into a can body cylinder deflects the metal at the end over the widening contour of the die to extend the metal outwardly and generally normal to the can body cylinder. The shape of the conventional flange die has been established by trial and error over many years of production experience. It is, however, found that sometimes split flanges may occur because of flaws in the material, or because blunt slitting cutters have been used, but above all, if work-hardened high tensile material with low elongation is used to make the can body cylinders.

When using the conventional die flanging principle it has been found possible to flange work hardened material, such as is known in the art as double reduced tinplate, only if the cylinder ends are in the direction of the grain of the material. It is a main object of the present invention to provide a method of and apparatus for flanging cylinders made of work hardened material while reducing flange splitting to a minimum.

SUMMARY

According to the invention there is provided a method of cold-forming a laterally extending flange at an end of a thin metal cylindrical body comprising the steps of supporting for rotation about parallel axes a circular flanging die and a swaging roller provided respectively with cooperating female and male radiused corners, axially aligning with the flanging die an end of a cylindrical body to be flanged, and while positively rotating the flanging die about the axis thereof engaging the inner and outer sides of the end of the cylindrical body while moving the flanging die and the swaging roller in opposite axial directions thereby simultaneously applying to the end of the cylindrical body tensile and compressive forces to effect forming of the flange on the body.

According to another aspect of the invention there is provided apparatus for cold-forming a laterally extending

2

flange at an end of a thin metal cylindrical body, comprising a circular flanging die and swaging roller supported respectively by spindles for rotation about parallel axes, said flanging die and swaging roller being provided respectively with co-operating female and male peripheral radiused corners, driving means operable to rotate the flanging die about its axis, means for axially aligning an end of a cylindrical body with the flanging die, and cams operable to move the flanging die and the swaging roller in opposite axial directions into engagement with the inner and outer sides of the end of the cylindrical body thereby simultaneously to apply tensile and compressive forces to the end of the body to effect forming of the flange. The swaging roller may be movable axially relative to the spindle therefor against the action of a spring.

BRIEF DESCRIPTION OF THE DRAWINGS

FIG. 1 is a diagrammatic top plan of a machine embodying apparatus according to the invention,

FIG. 2 is a section on line II—II, FIG. 1 and illustrates apparatus according to the invention,

FIG. 3 illustrates the timing of the apparatus,

FIG. 4 is a development of two cams embodied in the apparatus, and

FIGS. 5 to 10 illustrate the operation of a flanging die and swaging roller as controlled by the cams of FIG. 4.

DESCRIPTION OF THE PREFERRED EMBODIMENT

Referring to FIG. 1, can body cylinders 1 are fed by a worm-type conveyor 2 to a rotatable feed turret 3 having pockets 4 equipped with magnets 5, FIGS. 5 and 6, which engage the sides of the cans and align them axially with a circular flanging die 6, FIGS. 2 and 5 to 10. After flanging of the cylinder 1, as described below, the flanged cylinder is received by a pocket 7 of a rotatable ejecting turret 8 the pocket being equipped with a magnet 9, FIG. 10, which engages the side of the flanged can body and removes it from alignment with the flanging die 6 and discharges it to a discharge conveyor, not shown. A stripper member 10, FIG. 10, co-operates with turret 8 to effect removal of the flanged can body.

In the machine illustrated in FIG. 1 eight sets of flanging dies 6 and co-operating swaging rollers 11, FIGS. 2 and 5 to 10, are provided, each set consisting of two dies 6 and two rollers 11, as shown in FIGS. 5 to 10, to operate simultaneously to flange the opposite ends of a can body cylinder 1. Since the dies 6 and rollers 11 and the operating mechanism therefor is duplicated for the two ends of a cylinder 1 the flanging of only one cylinder end will be specifically described with particular reference to FIG. 2.

Referring to FIG. 2, the flanging die 6 and swaging roller 11 are respectively supported by spindles 12, 13 for rotation about parallel axes and the flanging die and swaging roller are respectively provided with co-operating female and male peripheral radiused corners 14, 15. The flanging die spindle 12 is positively rotated about its axis by driving means consisting of a pinion 16 which meshes with a stationary gear 17 co-axial with the axis of rotation of a carrier 18 with which the spindles 12, 13 are rotatable. The axis of rotation of the carrier 18 is parallel with the axes of the spindles 12, 13 and the carrier is rotatable with a shaft 19 which is driven by any suitable means, not shown. Cams 20, 21 are operable to move the flanging die 6 and the swaging roller 11 in opposite axial directions into and out of engagement with the inner and outer sides of the end of the cylinder 1 thereby simultaneously to apply tensile and compressive forces to the end of the cylinder to effect forming of the flange 1a.

The spindle 12 is rotatable in bearings 22, 23 mounted in a sleeve 24 which is slidably axially in the carrier 18

and the sleeve 24 is connected to a cam follower support 25 which supports cam followers 26 co-operating with the cam 20. The spindle 13 is freely rotatable in bearings 27, 28 mounted in a sleeve 29 fast in a cam follower support 30 which is slidable axially in the carrier 18. The bearings 27, 28 are eccentric to the axis of rotation of the carrier 18 to ensure sufficient radial pressure against the exterior of the cylinder 1.

Adjustment of the extent of eccentricity can be effected by suitable means, not shown. The cam follower support 30 carries cam followers 31 which co-operate with the cam 21.

The swaging roller 11 is movable axially relative to the spindle 13 against the action of a spring 32 which urges the roller against a shoulder 33 on the spindle 13. The leading of the spring 32 maintains the roller 11 against the shoulder 33 during flanging unless the preloading force is exceeded, as when the roller 11 is engaged by the longitudinal side seam of a cylinder, when the spring 32 permits controlled axial movement of the roller relative to spindle 11.

The flanging die 6 is provided with a peripheral annular abutment 34 which, as shown in the drawing, is arranged to determine the extent of overturning of the flange 1a and also frictionally to engage the face 35 of roller 11 to effect rotation of the roller 11 about its axis.

The mode of operation will be described with reference to FIGS. 3 to 10.

When a cylinder 1 is moved by turret 3 into axial alignment with the flanging dies 6, FIGS. 5 and 6 positions A and B FIG. 3, the flanging dies 6 and swaging rollers 11 under control of cams 20, 21 occupy the positions shown in FIGS. 5 and 6. When the cylinder has advanced to position C, FIGS. 3 and 4, the flanging dies 6 have entered the end of the cylinder and the cylinder has been released by magnet 5, FIG. 7. Rotation of carrier 18 continues the movement of the cylinder to position D, FIGS. 3 and 4 by which time the cams 20, 21 have caused the flanging dies 6 and swaging rollers 11 to occupy the positions shown in FIG. 8, the abutments 34 now engaging the faces 35 of the swaging rollers 11.

While the cylinder is being advanced between positions D and E, FIGS. 3 and 4, the flanging dies 6 and swaging rollers 11 co-operate simultaneously to apply tensile and compressive forces to the ends of the cylinder so as to form the flanges 1a, FIG. 9, and during this time the flanging dies 6 rotate about six times around their axes. Between positions E and F, FIGS. 3 and 4 cams 20 disengage the flanging dies 6 from the cylinder but the flanges 1a remain engaged by the swaging rollers 11 so that ironing to ensure consistency takes place between positions F and G. At positions F and G, FIGS. 3 and 4, the flanged cylinder is engaged by magnet 9 and the cylinder is tripped away from rollers 11 and is removed by the turret 8.

Although in the foregoing the method and apparatus have been described with reference to the simultaneous flanging of both ends of a cylinder it will be understood that, if desired, one end only of a cylindrical body can be flanged.

As stated above, the apparatus operates effectively with work hardened material and it also has the advantage that the radius of the corner 15 of a swaging roller can be reduced to a minimum and this is considered to be of advantage when the flanged cylinder has can ends double seamed thereto. It is also found that when the cylinders are formed with soldered lap joints, thick laps are reduced in thickness, and this reduces the tendency of the laps to split during the flanging operation. It is further thought by using the apparatus according to the invention to flange cylinders having welded seams, that the small notches previously required in the vicinity of the seam may be avoided.

I claim:

1. A method of cold-forming a laterally extending flange at an end of a thin metal cylindrical body comprising

the steps of supporting for rotation about parallel axes a circular flanging die and a swaging roller provided respectively with co-operating female and male radiused corners, axially aligning with the flanging die an end of a cylindrical body to be flanged, and while positively rotating the flanging die about the axis thereof engaging the inner and outer sides of the end of the cylindrical body while moving the flanging die and the swaging roller in opposite axial directions, thereby simultaneously applying to the end of the cylindrical body tensile and compressive forces to effect forming of the flange on the body.

2. Apparatus for cold-forming a laterally extending flange at an end of a thin metal cylindrical body, comprising a circular flanging die and a swaging roller supported by spindles for rotation about parallel axes, said flanging die and swaging roller being provided respectively with co-operating female and male peripheral radiused corners, driving means operable to rotate the flanging die about its axis, means for axially aligning an end of a cylindrical body with the flanging die, and cams operable to move the flanging die and the swaging roller in opposite axial directions into engagement with the inner and outer sides of the end of the cylindrical body thereby simultaneously to apply tensile and compressive forces to the end of the body to effect forming of the flange.

3. Apparatus according to claim 2, wherein the swaging roller is movable axially relative to the spindle therefor against the action of a spring.

4. Apparatus according to claim 2, wherein the flanging die is provided with a peripheral annular abutment arranged to determine the extent of overturning of the flange and frictionally to engage a face of the swaging roller to effect rotation of the roller about the axis thereof.

5. Apparatus according to claim 2, wherein the flanging die and swaging roller spindles are supported for rotation in a carrier and for axial movement relative to the carrier, the carrier is rotatable about an axis parallel to the axes of the flanging die and swaging roller spindles, a pinion secured to the flanging die spindle meshes with a stationary gear co-axial with the axis of rotation of the carrier, and the flanging die and swaging roller spindles have associated therewith cam followers co-operating with stationary cams co-axial with the axis of rotation of the carrier and arranged to effect said axial movements of the flanging die and swaging roller.

6. Apparatus according to claim 2, wherein the means for axially aligning a cylindrical body with the flanging die comprises a magnet movable with a feed turret and arranged to engage the side of the body.

7. Apparatus according to claim 3, wherein the flanging die is provided with a peripheral annular abutment arranged to determine the extent of overturning of the flange and frictionally to engage a face of the swaging roller to effect rotation of the roller about the axis thereof.

8. Apparatus according to claim 3, wherein the flanging die and swaging roller spindles are supported for rotation in a carrier and for axial movement relative to the carrier, the carrier is rotatable about an axis parallel to the axes of the flanging die and swaging roller spindles, a pinion secured to the flanging die spindle meshes with a stationary gear co-axial with the axis of rotation of the carrier, and the flanging die and swaging roller spindles have associated therewith cam followers co-operating with stationary cams co-axial with the axis of rotation of the carrier and arranged to effect said axial movements of the flanging die and swaging roller.

9. Apparatus according to claim 3, wherein the means for axially aligning a cylindrical body with the flanging die comprises a magnet movable with a feed turret and arranged to engage the side of the body.

10. Apparatus according to claim 3, wherein the flanging die is provided with a peripheral annular abutment arranged to determine the extent of overturning of the

flange and frictionally to engage a face of the swaging roller to effect rotation of the roller about the axis thereof, wherein the flanging die and swaging roller spindles are supported for rotation in a carrier and for axial movement relative to the carrier, the carrier is rotatable about an axis parallel to the axes of the flanging die and swaging roller spindles, a pinion secured to the flanging die spindle meshes with a stationary gear co-axial with the axis of rotation of the carrier, and the flanging die and swaging roller spindles have associated therewith cam followers co-operating with stationary cams co-axial with the axis of rotation of the carrier and arranged to effect said axial movements of the flanging die and swaging roller, and wherein the means for axially align-

ing a cylindrical body with the flanging die comprises a magnet movable with a feed turret and arranged to engage the side of the body.
